(57) **CLAIM**

The ornamental design for a racket head, as shown and described.

DESCRIPTION

FIG. 1 is a perspective view of the racket head showing my new design;

FIG. 2 is a front view, the rear view being the same image thereof;

FIG. 3 is a top view therefore;

FIG. 4 is a bottom view therefore;

FIG. 5 is a right side view, the left side view being the same image thereof; and,

FIG. 6 is a sectional view taken on line 6—6 of FIG. 1.

The broken lines in FIGS. 1 through 6 are for illustrative purpose only and form no part of the claimed design.
